TRAVELING CASE FOR GARMENTS

Frederick K. Bauer, P.O. Box 1705,
Beverly Hills, Calif. 90213

Filed May 13, 1974, Ser. No. 469,247

Term of patent 14 years

Int. Cl. D3—02

U.S. Cl. D87—1 R

FIG. 1 is a front perspective view of a traveling case for garments showing my new design;

FIG. 2 is a side elevational view;

FIG. 3 is a bottom plan view;

FIG. 4 is a rear elevational view; and

FIG. 5 is a top perspective view thereof in a flat condition.

I claim:

The ornamental design for a traveling case for garments, substantially as shown and described.
